VAULT STRUCTURE

Orestes Dioguardi, Jr., Brooklyn, N. Y.

Application August 29, 1952, Serial No. 307,137

4 Claims. (Cl. 27—35)

1

This invention relates generally to vault structures and more particularly to a burial vault construction.

It is a known fact that according to cemetery burial regulations and religious customs not more than 3 caskets may be placed in superposed position in a single burial plot or area. To arrange these caskets in separate vaults or outer burial cases has caused difficulties as to the height of such vault structures since they are not to exceed a predetermined measurement. The consequence of such requirement is that vaults must not only be dimensioned to fit various shapes of caskets, but cannot exceed a definite maximum height in order to comply with the aforesaid regulations, must be sturdy and assume a shape or configuration in order to enable placing of three vaults in superposed position within a single burial plot.

It is, therefore, one of the objects of the invention to provide means facilitating a strong and substantially fluid-tight vault structure for housing variously shaped caskets and to withstand for a long time atmospheric influences, outer pressures, and other forces.

It is another object of the invention to provide means affording a suitably formed lid or cover structure which may be easily grasped and handled and does not in any way contribute to an increase of the height of the vault and like case.

It is a further object of the invention to provide means conducive to convenient accommodation of the locking mechanism for the vault structure and its operation from within hollow handles, whose upper walls are substantially level with the uppermost lid surface.

It is another object of the invention to provide means permitting positive guidance and locking of the lid with respect to the vault body and also ready unlocking and removing of said lid therefrom, if desired.

It is still another object of the invention to provide means affording positive and automatic locking of the lid or cover structure on the body of the vault when the lid is lowered on top of the latter.

It is a still further object of the invention to provide means rendering the possibility of manufacturing from a single, thin or light-gauged sheet metal, such as steel, a strong vault structure without the need of additional reinforcing braces or like elements.

It is another object of the invention to provide means contributing to a thin-walled vault

2

structure which is reinforced in longitudinal and transverse directions of its walls so that they withstand high pressures without suffering distortion and deformation.

5 It is yet a further object of the invention to provide means conducive to easy removal from the vault of supporting web straps generally used for lowering of the casket for contact with the bottom of the vault.

10 It is a still further object of the invention to provide means affording easy change of appearance of a steel or like metal vault into a concrete vault.

15 The above and other objects and features will become apparent from the following detailed description, reference being had to the accompanying drawings, in which:

Fig. 1 is a transverse section through the vault constructed in accordance with the present invention;

20 Fig. 2 is an enlarged, fragmentary sectional view of details of the locking mechanism used in connection with the invention;

Fig. 3 is an end view of the locking mechanism of Fig. 2;

25 Fig. 4 shows a front view, partly in section, of a side wall of the vault;

Fig. 5 is a section of the side wall shown in Fig. 4;

30 Fig. 6 is a detail fragmentary top plan view of the bottom wall of the vault; and

Fig. 7 is a fragmentary, perspective view of a vault structure in modified form, showing an end wall of the vault in the process of being swung into engagement position with the vault.

35 Referring more particularly to the drawings, Fig. 1 shows a burial vault 10 adapted to receive a casket 11 seen in phantom lines. Vault 10 is constituted by a casing 12 and a lid 13. Said casing 12 includes upright side walls 14 and bottom wall 15. Side walls 14 are provided at their upper ends with an inwardly extending circumferential flange 16 having a groove 16b and a guiding edge 17. Lid 13 is also provided with an inwardly extending circumferential flange 18 including a guiding edge 19. Guiding edge 19 is provided with spaced cut-outs 20, threaded openings 21 engaging bolts 22 which support springs 23 each being offset at one of its ends 24 which lies adjacent the respective cut-out 20.

40 Pivot pin 25 is connected to the inside wall of each guiding edge 19 and extends across cut-out 20. Latch means 26 pivoted on pins 25 substantially extend within each cut-out 20 and 45 include each a central portion 27 and flange

50 55

means 28 with an arcuate surface 29. Springs 23 abut against the central portions 27 and thereby urge latch means 26 in the direction of arrow A (Fig. 2). To each latch means 26 is connected a pull cord 30. The lid 13 is further provided with hollow handles 31 affixed adjacent opposite ends of the lid 13. Within the lid are arranged gasket-shaped sealing means 33 surrounding openings 32 through which said pull cords 30 are conducted. Each pull cord 30 terminates in a ring member 34 attached at the end thereof.

As can be seen from the drawings, each handle 31 consists of a substantially flat top piece 35 which is substantially level with the top wall 15 36 of the lid 13.

Handle 31 has further downwardly extending lugs 37 and 38 which are spaced from each other and fixed to the downwardly slanting wall portions 36a of the lid, as by welding. It will further be seen from the drawing that handle top piece or wall 35 includes a tubular piece 39 at one end to thereby facilitate grasping of the lid 13 by an operator standing at one end thereof. Within the space between the lugs 37, 38 which define a pocket the ring member 34 becomes accessible, so that a person grasping with both hands the opposite handles 31 may also pull by means of ring members 34 the pull cords 30 to thereby unlatch the lid 13 from the casing 12 30 for removing the lid from the latter.

The uppermost surfaces of the top walls 35 of the handles, which are arranged on the slanting lid surface side portions are flush with the central uppermost surface wall 36 of the lid. Thus, the handles 31 cooperate with the top wall 36 and form an enlarged bearing surface for supporting another vault 10a, shown in phantom lines, which may be stacked thereon. The further downwardly extending, substantially 40 vertical side walls 14 include reinforcing means in the form of bent portions 40. Other reinforcing means may be provided; for instance, the side walls 14 may be made of sheet material which is hammered or undulated either longitudinally or transversely thereof, or both. The bottom wall 15 is hammered and thus reinforced, and it includes indentations or protuberances 41, 42, 43 and 44 which are symmetrically arranged. The casket 11 is supported by said protuberances 41, 42, 43 and 44, and it is spaced from the inner surface of bottom wall 15, so that when the casket has been lowered into the vault 10 the web strap means 45, which is generally used, may be easily removed.

The vault is made from light or thin-gauged sheet material such as steel. Additional concrete reinforcing means may be provided, if such is deemed desirable, as is explained further below.

As more clearly illustrated in Fig. 2 upon lowering of lid 13 onto casing 12 the guide edges 19 and 17 of the respective flange means 18 and 16 tend to center and guide the lid with respect to the open-ended casing, while sealing means 16a of rubber, rubber cement or any suitable and compressible sealing strap material running along and seated in circumferential groove 16b is firmly compressed and in contact with said flange 18 to provide a perfect air- and fluid-tight seal, which is recessed and invisible with respect to the outer surfaces of the lid and side walls of the casing. Latch means 26 then spring into action to automatically lock said lid in position as is well apparent from the above description. Referring to Figs. 4 and 5, there is dis-

closed the outer surface 40' of an upright side wall 41', which is corrugated at 41a', 41b', etc. and may have openings 42' in said corrugations for a purpose hereinafter described. It is well understood that side walls 14 as well as bottom wall 15 may be replaced by corrugated thin steel walls 41', the corrugations thereof running in the direction from the upper flange 16 downwardly toward bottom wall 15 (Fig. 5).

In order to change the outer appearance of the vault or otherwise comply with any desired wishes of customers the corrugated steel wall casing or vault may be readily transformed into a casing with concrete wall appearance. To this end, the corrugated portions 41a', 41b', etc. are provided with the aforesaid openings 42' in which are anchored and retained portions of layers of concrete mass 43' which becomes contiguous with the outermost apices 40a of the wall 41'. Fig. 4 shows a front elevation of transformed corrugated wall 41' with outer concrete appearance.

In conjunction with the aforesaid corrugated side walls the bottom wall 15 of the casing 12 may be reinforced at the inner surface thereof by hammering at 50 or by other suitable displacements of portions of the material of which the casing is made. Those parts of the bottom wall 15 on which the casket 11 is placed may be provided with somewhat elevated pairs of protuberances or tits 41, 41a; 42, 42a; 43, 43a and 44, 44a, which not only contribute to stiffening of the bottom plate, but also facilitate ready removal of web means 45, by means of which casket 11 may be lowered into the interior of the casing and onto the bottom 15 thereof.

It is to be understood that instead of closing or locking vault 10 from above, one of the end walls 51 of the casing 10b (Fig. 7) may be employed to close and lock the casing in a manner similar to that described with respect to lid 13, which, in such case, would be fixed to or integral with the remainder of the casing. In such a case, a frame having a flange 52 and guiding means substantially similar to that of side walls 14 may be secured endwise to the side walls of the vault. The top wall 36b of vault 10b has the laterally fixed handles 31b disposed adjacent wall portion 36b to enlarge the bearing surface of said portion 36b.

Instead of being made from steel, the vault may be made from any suitable plastic or plastic composition, wood and other material sustaining high stresses and other forces.

The invention has been shown and described in general in the drawings. However, it should be noted that this invention may be realized in modified form and adaptations of the arrangements herein disclosed may be made as may readily occur to persons skilled in the art, without constituting a departure from the spirit and the scope of the invention as defined in the objects and in the appended claims.

Having thus described the invention, what is claimed as new and desired to be secured by Letters Patent, is:

1. A burial vault and like structure comprising a top wall, upright side walls, said top wall including a substantially horizontal wall portion and inclined wall portions diverging from said horizontal wall portion toward said upright side walls, and handle means disposed adjacent said inclined wall portions at predetermined spaced locations of the latter, said handle means including each a top piece extending substantially

level with said horizontal wall portion, whereby the bearing area of the latter is enlarged for supporting another vault in superposed position thereon.

2. A structure according to claim 1, wherein each of said handle means comprises spaced lugs extending at opposite ends of said top piece to the respective inclined wall portion, to which said lugs are attached.

3. A structure according to claim 1, wherein 10 said top piece of each handle means is reinforced by a tubular end extending below and across said top piece.

4. A structure according to claim 1, wherein each top piece has a reinforced tubular end portion, and lateral lugs extending between each top piece and the respective inclined wall portion, each of said handle means forming together with the respective inclined wall portion a pocket.
